2,548,836

ELECTROMAGNETIC FIELD PHASE
DETERMINING APPARATUS

Harvey R. Worthington, Jr., Cambridge, Mass., assignor, by mesne assignments, to the United States of America as represented by the Secretary of War.

Application July 9, 1945, Serial No. 604,032

7 Claims. (Cl. 343—100)

1

2

This invention relates to electrical apparatus and more particularly to apparatus used in relative phase measurements and determination of surfaces having a wavefront of uniform phase in electromagnetic energy radiating devices.

In the design of electromagnetic energy radiating elements it is desirable to be able to explore and plot the uniform phase wavefront of the energy emanating therefrom. Such plots of uniform phase wavefront aid in the design of the radiating element and of its point and manner of feed.

An object of the present invention is, therefore, to provide an electrical device for exploring with a high degree of sensitivity and accuracy the electromagnetic wavefront surfaces surrounding a radiating element.

For a better understanding of the invention, together with other and further objects thereof, reference is had to the following description, taken in connection with the accompanying drawing in which:

Fig. 1 shows schematically one embodiment of a phase measuring device; and

Fig. 2 shows another embodiment of a phase measuring device.

Referring now particularly to Fig. 1 of the drawing there is shown a phase measuring device which comprises an oscillator 11 which feeds radio frequency energy through a transmission line 12 to a radiating element 13. The line 12 may be open-wire, coaxial or wave guide depending upon the frequency of the oscillator 11. The radiating element 13 is any desired type of radiator, dipole, horn, parabola, etc., the wavefront surfaces of which it is desired to investigate. The line 12 is provided with a phase shifter 14 and connects to a second similar transmission line 15 by means of a direction coupler 16 which may be a waveguide section having two irises spaced so as to match line 15 to line 12 and permit energy from oscillator 11 to be coupled to line 15, yet not permit energy from radiating element 13 to be coupled to line 15. Any other of the several well known types of directional couplers may be used. Directional coupler 16 is disposed intermediate the oscillator 11 and radiactor 13. The line 15 is provided with a flap-type attenuator 21 and connects to one branch of a magic-T 22. A

magic-T is a well known type of matched directional coupler for microwaves and is an analogue of the hybrid coil used for low frequencies. The magic-T coupler is described in the following pending applications: Robert L. Kyhl, S. N. 580,014, filed February 27, 1945, now abandoned, 55

and Robert H. Dicke, S. N. 581,695, filed March 8, 1945, and S. N. 586,413, filed April 3, 1945. The magic-T is also described on pages 306-308 of "Principles of Microwave Circuits" by C. G. Montgomery, R. H. Dicke and E. M. Purcell. A magic-T has four waveguide branches; the first two branches being collinear, the third being perpendicular to the first two branches, and the fourth branch being perpendicular to the plane formed by the other three branches. A pickup section of line 23 is connected to the magic-T 22 at one end and the free end thereof is used to explore the wavefront surfaces of the radiating element 13. The pickup line 23 may be mechanically adapted to be moved in an arc or straight line as desired. A square-law type detector 24, preferably of the silicon crystal type, is inserted in one branch of the magic-T 22 in such a manner as to receive energy from line 15 and line 23. The remaining branch of the magic-T 22 is terminated in a matched load 25. The dotted portion 26 of the line 15, Fig. 1, indicates that line 15 is very long compared to line 12 plus line 23. The detector 24 feeds an amplifier 31 which in turn controls the vertical deflection of a cathode ray oscilloscope 32. The sawtooth sweep voltage of the oscilloscope 32 is fed to the oscillator 11 in such a manner as to produce frequency modulation of this oscillator.

In the operation of the device of Fig. 1 energy from the oscillator 11 travels through line 12, element 13, the free space between element 13 and line 23, and line 23, and arrives at the detector 24. The total path length enumerated above will be designated D_1 . At the same time energy from the oscillator 11 arrives at the detector 24 via coupler 16 and line 26. The length of this path is denoted D_2 .

With the pickup section 23 at some fixed point and at a particular frequency f the phase shifter 14 can be adjusted so that the energies arriving at the detector 24 are 180° out of phase, the result being that the output of the detector 24 will be a minimum and hence the deflection of the oscilloscope 32 will be a minimum. It is well known that if two energies of the same frequency are combined, the amplitude of the resultant is dependent upon the relative phases of the two energies. Furthermore it will be noted that if the relative phase of the two energies is varied continuously and linearly with time through one complete cycle, the output of the detector will vary sinusoidally with time. To accomplish this variation of relative phase it is proposed to vary the oscillator frequency linearly with time. It

can be shown that the relative phase between two energies at the ends of two lines of length D_1 and D_2 , where the difference of D_1 and D_2 is denoted by L , is given by:

$$(1) \quad \Delta\phi = -\Delta f \frac{\delta}{\delta f} \left(\frac{2\pi L}{\lambda g} \right)$$

In the above expression $\Delta\phi$ is the change in relative phase of the energies at the ends of the lines of length D_1 and D_2 , Δf is the change in frequency which brought about the change in relative phase, f is the initial frequency, L is as specified above and λg is the electrical wavelength as measured within the transmission line. Equation 1 can be simplified to the following expressions:

$$(2) \quad \Delta\phi = 3\pi L \Delta f \frac{\delta}{\delta f} \left(\frac{1}{\lambda g} \right)$$

$$(3) \quad \Delta\phi = 2\pi L \frac{\Delta f}{f} \left(\frac{\lambda g}{\lambda^2} \right)$$

and for rectangular wave guides to

$$(4) \quad \Delta\phi = \frac{2\pi L \Delta f}{C \sqrt{1 - \left(\frac{\lambda}{2a} \right)^2}}$$

In the above equations, in addition to the symbols already designated, λ is the wavelength in air, C is the velocity of light and a is the broad dimension of the rectangular guide.

As before stated, if the relative phase of the two energies is varied through one cycle, the output of the detector will complete a one-cycle variation. Therefore, by setting

$$(5) \quad \Delta\phi = 2\pi = 360^\circ$$

in Equation 3 or 4 above, a solution may be obtained for either the length L , which is the difference of D_1 and D_2 , or Δf , the frequency change. One of the two dependent variables must of necessity be chosen arbitrarily.

It can be seen that the frequency of the sinusoidal output of the detector depends upon the modulation frequency of the oscillator 41. The sweep voltage of the oscilloscope 32 is used to modulate the oscillator with the result that one complete sine wave will be observed in the oscilloscope.

If now the pickup section of line 23 is moved, the shift of the oscilloscope pattern will indicate the change in phase in the field of the radiating element. If the pickup section 23 is moved in such a manner as to prevent movement of the oscilloscope pattern, the movement will be along a uniform phase wavefront surface.

Referring now to Fig. 2 there is shown an improved phase measuring device which comprises an oscillator 41, similar to oscillator 11, which feeds radio frequency energy through a transmission line 42, similar to line 12, to a radiating element 43, similar to element 13. The line 42 is provided with a phase shifter 44 and is connected to a second transmission line 45 by means of a directional coupler 46. The line 45 is provided with a standing wave detector 51 and connects to a mixer 53 by means of directional coupler 54. An iris 55 is inserted in the line 45 at point C to provide reflection therefrom. The dotted portion 56 of line 45 indicates a very long line. A pickup section of transmission line 61 is adapted to be moved in the field of the element 43 to permit investigation of the constant phase patterns. The line 61 connects to the mixer 53. The output of the mixer 53 feeds through an amplifier 62 to

the horizontal set of deflection plates of a cathode ray oscilloscope 63. The output of the standing wave detector 51 feeds through an amplifier 64 to the vertical set of deflection plates of the oscilloscope 63. Sweep voltage from the oscilloscope is fed to the oscillator 41.

The operation of the device of Fig. 2 is similar fundamentally to that of the device of Fig. 1 and therefore only the points of difference will be discussed.

Energy from the oscillator 41 passes via the two paths hereinbefore described to the mixer 53. If the frequency of the oscillator changes in accordance with the previous discussion, the output of the mixer 53 will be a voltage of sinusoidal waveform. The phase of this result sine wave is dependent upon the phase plane in which the pickup line 61 lies. It is desired to obtain a reference sine wave having the same frequency but which is independent of the position of the pickup line 61. With the pickup line 61 in a fixed position, which will be taken as the reference position, there exist two points A' and B' at which energy from the oscillator 41 exhibits the same properties as at A and B at the mixer 53. The distances A' to A and B' to B are equal. There also exists energy at a point A'' which has all the properties of the energy at point A', A' and A'' being equidistant from the oscillator 41. The iris 55 is placed at a point C which is equidistant from point A'' and point B'. The energy which is reflected from the iris 55 will arrive back at B'' with the same properties it would have had at B'. As a result of the foregoing, there appear at the standing wave detector 51 two energies whose relative phases are not dependent upon the position of the pickup line 61 but which behave in the same manner as the energy at the mixer 53 to produce a voltage which is sinusoidal. When the pickup line 61 is in the reference position, the outputs of the mixer 53 and detector 51 will be in phase and the resultant pattern in the oscilloscope 63 will be a straight line. When the pickup line 61 is moved and does not remain within a surface having a wavefront of uniform phase the oscilloscope pattern will become an ellipse. The standing wave detector 51 can be moved to reduce the ellipse to a straight line and the amount of the deviation can be read from a calibration on the detector 51.

While there has been described what are at present considered the preferred embodiments of the invention, it will be obvious to those skilled in the art that various changes and modifications may be made therein without departing from the invention.

What is claimed is:

1. A phase measuring apparatus comprising, in combination with a cathode ray oscilloscope and a radiating element, a variable-frequency oscillating means, means connected to said oscillating means for varying the frequency thereof repeatedly and linearly with time, first transmission means connecting said oscillating means to the radiating element, a magic-T having two symmetrical and two asymmetrical branches, mixer means inserted in one of the symmetrical branches of said magic-T, matched loading means terminating the remaining symmetrical branch of said magic-T, second transmission means connected to one of the asymmetrical branches of said magic-T, directional coupler means for connecting said first transmission means to said second transmission means, third transmission means connected to the remaining asymmetrical branch of said magic-T and movable with respect to said

radiating element and in the field of the radiating element for exploring the wavefronts of said field, and amplifier means connecting the output of said mixer means to the oscilloscope whereby indications of surfaces of uniform phase in the field of the radiating element may be observed thereon.

2. A phase measuring apparatus comprising, in combination with a cathode ray oscilloscope and a radiating element, a variable-frequency oscillating means, means connected to said oscillating means for varying the frequency thereof repeatedly and linearly with time, first transmission means connecting said oscillating means to the radiating element, second transmission means, first directional coupler means for connecting said first transmission means to said second transmission means, mixer means, third transmission means connected to said mixer means and movable with respect to said radiating element and in the field of the radiating element for exploring the wavefront thereof, second directional coupler means for connecting said second transmission means to said mixer means, standing wave detector means coupled to said second transmission means, reflector means in said second transmission means intermediate said standing wave detector means and said mixer means, first amplifier means connecting the output of said mixer means to the oscilloscope, and second amplifier means connecting the output of said standing wave detector means to the oscilloscope whereby indications of surfaces of uniform phase in the field of the radiating element may be observed thereon.

3. A phase measuring apparatus comprising, in combination with a cathode ray oscilloscope and a radiating element, a variable-frequency oscillator, mixer means, first transmission means for applying signals from said oscillator to said radiating element, second transmission means movable with respect to the radiating element and in the field of said radiating element for exploring the said field and for receiving and applying said signals to said mixing means, third transmission means for applying signals from said oscillator to said mixer means directly, and means for connecting the output of said mixer to the oscilloscope whereby indications of wavefronts of uniform phase in the field of the radiating element may be observed thereon.

4. A phase measuring apparatus comprising, in combination with a cathode ray oscilloscope and a radiating element, a variable-frequency oscillator, mixer means, first transmission means for applying signals from said oscillator to said radiating element, second transmission means movable with respect to the radiating element and in the field of said radiating element for exploring the said field and for receiving and applying said signals to said mixer means, third transmission means for applying signals from said oscillator to said mixer means directly, means for connecting the output of said mixer to the oscilloscope, standing wave detector means coupled to said third transmission means, reflector means in said third transmission means intermediate said standing wave detector means and said mixer means, and means for applying the output of said standing wave detector to the oscilloscope whereby indications of wavefronts of uniform phase in the field of the radiating element may be observed thereon.

5. A phase measuring apparatus comprising, in combination with a cathode ray oscilloscope and

a radiating element, an oscillator, mixer means, first transmission means for applying signals from said oscillator to the radiating element, second transmission means for applying signals from said oscillator to said mixer means, third transmission means connected to said mixer means and movable with respect to the radiating element and in the field of the radiating element for exploring the wavefronts of said field, means connected to said second transmission means for varying the relative phase of the signals arriving at said mixer means from said second and third transmission means repeatedly and linearly with time, and means for applying the output of said mixer means to the oscilloscope whereby indications of surfaces having a wavefront of uniform phase in the field of the radiating element may be observed thereon.

6. An electromagnetic field mapping apparatus comprising a variable frequency oscillator, a radiator, mixer means, means for coupling said oscillator to said mixer means and said radiator, a radiation receiving probe movable with respect to said radiator and from point to point in the field of said radiator, means connecting said probe to said mixer means, means connected to said oscillator for varying its frequency cyclically, to thereby produce an alternating current at the output of the mixer means, and a phase indicating means connected to the output of said mixer means, whereby a wavefront of the field of said radiator may be determined by moving the probe over a surface in the field of the radiator without changing the phase of the alternating current output of the mixer means.

7. An electromagnetic field mapping apparatus comprising a variable frequency oscillator, a radiator, mixer means, a first means for coupling said oscillator to said mixer means and said radiator, a radiation receiving probe movable with respect to said radiator and in the field of said radiator, second means connecting said probe to said mixer means, a cathode ray tube oscilloscope connected to said mixer means, said oscilloscope including means for cyclically sweeping the electron beam of its cathode ray tube, third means connected to said oscillator for cyclically varying the frequency of said oscillator linearly with time and in synchronism with the sweep of the cathode ray tube beam to thereby produce an alternating current output from the mixer means, said third means varying the frequency of said oscillator throughout a range sufficient to produce an integral number of half cycles of said alternating current at the output of the mixer during each sweep of the cathode ray tube beam, whereby a wavefront of the field of said radiator may be determined by moving the probe over a surface in the field of the radiator without changing the phase of the alternating current output of the mixer means as indicated on the oscilloscope.
